UNITED STATES PATENT OFFICE

WILLIAM F. GROENE, OF CINCINNATI, OHIO, ASSIGNOR TO THE R. K. LE BLOND
MACHINE TOOL COMPANY, OF CINCINNATI, OHIO, A CORPORATION OF DELAWARE

LAPPING MACHINE

Application filed February 7, 1928. Serial No. 252,588.

My invention relates to lapping machines in which the bearings and the crank pins are lapped and polished to a true bearing surface in such a way as to approach very nearly 5 actual working conditions of the shaft.

Prior practice necessitated separate operations for lapping the main bearings and the crank pins, while my machine laps the bearings and the pins in one operation, thus producing concentric working surfaces with relation to the true centers of the crank shaft 10

Other advantages, novel structures and improvements over other mechanisms for like purposes will be pointed out as the description proceeds, in which I will set forth in detail one preferred embodiment of my invention and the novelty inherent, wherein I will state in the appended claims.

In the drawings:—

20 Figure 1 is a front elevation of the lapping mechanism.

Figure 2 is a top plan view of the machine.

Figure 3 is a perspective of the rear of the machine.

25 Figure 4 is a vertical section through the machine showing the levers collapsed with the lapping arms in lapping position.

Figure 5 is a vertical section through the machine showing the levers and the lapping 30 arms expanded.

Figure 6 is a complete lapping unit detached from the machine.

Figure 7 is an elevation of the head stock and driving mechanism of the machine.

25 Figures 8 and 9 are a top plan and front elevation of the spindle timing ratchet.

Figure 10 is a section through the head stock showing the component parts of the spindle and driving mechanism.

40 Figure 11 is a section through the eccentric taken on the lines 11—11 of Figure 7.

Figure 12 is a diagrammatic perspective of the air supply to the cylinders.

45 Figure 13 is an alternate form of the lapping unit.

Figure 14 is a diagram of the electric time control.

In my machine the head and tail stocks are 50 rigidly mounted on a separate bed plate which has lateral motion along the ways of

the main bed of the machine, while the lapping arms are confined in fixed vertical planes. This lateral motion is derived from an adjustable eccentric mounted within the head stock. 55

The revolving crank shafts impart reciprocating motion to the lapping arms which are guided and held from lateral movement. Each arm can be fitted with grinding stones or a solid block, whichever is preferred. 60

Lubrication to the lapping surfaces is provided through a series of tubes coming from a common source such as a circulating pump. The pressure for lapping is obtained by means of springs compressed a determined amount to limit the depth of lap for a given number of revolutions of the crank shaft. The springs limit the depth of lap automatically because the pressure exerted by them is gradually decreased to zero while the springs are returning to normal unflexed condition. These springs also bring the lapping arms together as they move into position on the surfaces of the pins and bearings. 70

75 Each pair of lapping arms is mounted as a single unit and supported by bearings mounted on a shaft. This shaft is rigidly mounted on a pivoted member which carries the lapping arms, their guides and lubricating hose away from the crank shaft when air is passed into a cylinder located within the lines of the bed of the machine.

The above mentioned member does not come into play before an outer member has been thrown back by means of another cylinder which actuates a toggle between the two members and causes them to separate. The inner member does not move until the limit of the toggle has been reached. Simultaneously, while the limit of the toggle is reached, the lapping arms are locked from sliding by a chain pulling on a latch mounted within the bearings of the lapping arms. Mounted on the outer member there is a cam which operates two whistle valves through which the air is excluded from the vertical cylinder and by-passed into the second horizontal cylinder below the bed of the machine. This by-passing of the air to the horizontal cylinder causes the pistons to swing the inner 90 95 100

and outer members away from the machine as a single unit and consequently draw the lapping arms away from the crank shaft in such a manner that they will be in their proper position to come forward and receive the next crank shaft when it has been put in the machine.

The return to position of lapping is a reverse sequence of operation as described for the removal of the work.

My machine stops after a predetermined number of revolutions of the crank shaft necessary to produce the proper bearing surface. This is accomplished by means of a suitable 15 electrical time element shown diagrammatically in Figure 14. My machine can also be stopped at will by suitable mechanism described later. While the machine can be stopped during any part of a revolution, it 20 is essential that the crank shafts be removed and installed while in a definite position so as to provide a constant relation of the shafts to the lapping arms. I have accomplished this by means of a ratchet and slidably 25 mounted stopping post. This stopping post cannot be operated before the power to the spindle driving the crank shaft has been disconnected. The power is applied through any suitable clutch arrangement combined 30 with a spindle and face plate similar in construction to lathes.

I have shown the main stand or bed 1 upon which is mounted a sliding plate 2 confined to a definite reciprocating motion by the eccentric 3 rotatably mounted in the head stock 4 and sliding block 5. Since the head stock and tail stock 5 are fixedly mounted on the base plate 2 they move back and forth with the base plate as a single unit, and thereby 35 transmit horizontal reciprocating lateral motion to the crank shaft 6 when it is placed between the centers of the head and tail stocks.

The eccentric 3 consists of a shaft 7 having keyed thereon the gear 8 which meshes and is 40 driven by the gear 9 keyed on the main spindle 10. The shaft 7 is journaled in the head stock at 7^a, 7^b, and has an eccentric portion 11 on its left end which protrudes beyond the outside of head stock. Upon this eccentric end 11 I mount a bushing 12 with an eccentric drilled hole 12^a therein. After assembling these parts I rotate the bushing 12 on the eccentric end of the shaft so as to fix the movement of the sliding plate 2 to the desired 45 amount. I then clamp the bushing fast to the eccentric of the shaft by means of the lock-nut 14. The rotation of the two eccentrics as a single unit within the sliding block causes the sliding plate to move back and forth because the sliding block is confined in the bifurcated member 15 which is fixed on the main stand of my machine. Since the sliding block 5 is confined to movement in the vertical plane and the sliding plate 2 in the 50 horizontal plane, it is apparent that the re-

sultant motion of the sliding plate is a horizontal reciprocating motion due to the eccentric circle described by the surface of the bushing 12 with relation to the center of the hole in the sliding block. Varying the relation between the eccentric 11 and the bushing 12 makes it possible for me to obtain any desired amount of movement of the sliding plate within the limits of zero and twice the eccentricity of the hole in the bushing.

The head stock consists of a spindle 10 supported in bearings at 10^a—10^b and driven through a clutch 17 by the pulley 18. Within the spindle is mounted a spring seated center 19 which automatically compensates for the slight variations encountered in the 70 lengths of the crank shafts.

Disengagement of the clutch is accomplished by clockwise motion of the lever 20 pinned to the shaft 21. The shaft 21 has 75 mounted thereon a fork 22 which engages the slidably mounted collar 23 on the spindle 10. This collar has a through pin 24 free to slide in a slot 25 in the spindle and connects the collar 23 with the clutch release rod 26 which 80 disengages the clutch through the adjustable bell crank 27. The face plate 28 of the spindle contains a stud 29 which engages and drives the crank shaft to be lapped, as 85 will be described below.

In order to index the crank shaft with relation to the lapping arms I have rigidly mounted on the spindle a ratchet wheel 30 having a shrouded portion 30^a with a stopping point slot 31 which is engaged by the 90 sliding latch 32 mounted in the head stock 4. This latch is confined to horizontal movement and is moved by the lever 33 on the shaft 33^a which has a pinion 34 fastened thereon and engages the rack teeth 35 cut on 95 the latch.

As a matter of precaution I provide an interlock pin 36 held slidably in a housing 36^a which inhibits the movement of lever 33 until the power to the machine has been cut off by throwing lever 20 manually or automatically, as will be noted. The lever 20 is a bell crank and is connected with the solenoid 37 through the link 38. This is provided so that the machine will stop automatically 100 after a predetermined number of revolutions when current to the solenoid is cut off by means of a suitable time element, shown diagrammatically in Figure 14. When the lever 20 on the lathe is thrown to engage the clutch a small limit switch 37^a, which has contacts normally held open by a spring, 105 will also be depressed, closing the contacts, which will energize a relay 37^b. After a definite time has elapsed, as determined by the setting of the relay, a contact will be closed in the relay between the terminals t, t', causing the contactor 37^c to pick up and in turn energize the solenoid, which will trip out the clutch and throw the lever 20 back 110

to the stop position, which will release the limit switch and cause it to open its contacts. This in turn will de-energize the relay, which will reset and de-energize the contactor and solenoid, leaving the equipment ready for a new start.

The shaft 33^a and the shaft 21 have cams 40 and 41 thereon. Power to the machine is cut off by rotating the shaft 21 with the lever 20 in a clockwise direction. When the shaft 21 is rotated in this direction it rotates the surface 41^a of cam 41 away from the bottom end of the interlock bar 36 which falls down to the position shown and allows its upper end to slide on the surface of the cam 40. The lever 33 can now be rotated in a clockwise direction and pull the latch 32 to the left where it will engage the slot 31 and index the spindle for removing the crank shaft 20 that has been lapped. The interlock bar 36 is slidably mounted in the housing 36^a rigidly mounted on the head stock. By referring to Fig. 7 it can be seen that lever 20 cannot be rocked to the left until the notch 32^a in 25 the latch 32 has been moved to the right and bridge the shroud of the ratchet wheel which will then be free to revolve. The lever 33 must rotate the cam 40 away from the upper end of the interlock bar 36, because the lower 30 end of the interlock bar 36 can not ride up over the surface of the cam 41^a while its upper end is against the surface of the cam 40, which prevents the interlock bar 36 from sliding upward. The machine is at rest and 35 the spindle is indexed for the next crank shaft to be lapped when the parts are in the positions shown in full lines in Fig. 7.

If the slot 31 on the ratchet wheel, which is part of the spindle, passes the latch 32 it 40 can be brought to the point of engagement by rotating the ratchet wheel with an up and down movement of the pawl handle 42 mounted on a projecting surface 43 of the ratchet wheel and held in place by the plate 44 which 45 is screwed to the face plate of the spindle. This plate does not interfere with the free movement of the pawl handle. The pawl 45 mounted on the pawl handle does not engage the ratchet wheel until it is lifted off the 50 trip 45^a mounted on the sliding plate 2. This trip prevents the pawl from riding the ratchet wheel while rotating during the lapping operation. The pawl 45 engages the ratchet wheel when the compression on the 55 spring 46 is released by raising the pawl handle so that the pawl tip 45^b does not bear on the trip 45^a.

Since each fly wheel flange of crank shafts have holes therein, I utilize these holes to 60 drive the crank shaft by placing stud 29 in one of them while placing the crank shafts between centers. The holes are jig drilled thereby enabling me to properly and definitely locate the crank shaft quickly because the 65 stud 29 and the slot 31 are fixed on the spindle

with relation to each other. By placing the stud in the same hole on each crank shaft, I automatically locate the crank pins and bearings with relation to the lapping arms and do not have to delay the lapping operation by locating each lapping unit separately. This is also advantageous because I put in and remove the crank shafts when the lapping arms are expanded and away from the machine.

Figures 6 and 13 show two types of lapping arms which may be used on my machine. The difference between the two is in the spring control element.

The lapping arms 47 and 48 are arranged in pairs, using as many pairs as desired. In the one type a spring 46 is fastened in the lapping arm 47 and passes through a boss 48^a on the lapping arm 48 and connects to a threaded stud 49 having on it a wing nut 50 which bears on the boss 48^a. By screwing down or up on the wing nut 50 I increase or decrease the tension of the spring and hence the lapping pressure. The lapping arms have concave surfaces 47^a and 48^b upon which I fasten lapping stones 52 of sufficient thickness to elevate them above the concave surfaces thereby providing ample clearance for the lubricant to carry away all chips or foreign matter which would mar the surface being lapped. The lubricant is supplied from a pump 53 at the rear of the machine and driven by means of a belt 54. The lubricant passes from the pump through the flexible hose 55 to the manifold pipe 56 mounted on the movable frames (to be described) into individual flexible hoses 57 and finally through the tubes 48^c in the lapping arm 48 onto the surfaces being lapped. After dropping from the surfaces being lapped the lubricant flows into a basin 51^a where it may be filtered and re-circulated. This manifold supply system enables an equal distribution of the lubricant sufficient to produce the best results.

Each of the lapping arms is rigidly mounted in the tubular rods 61 and pinned therein by the pin 61^a. These tubular rods are then pinned to the sliding blocks 62 by the pin 62^a. The sliding blocks 62 are the means provided to confine the lapping arms in the vertical planes and do so because they in turn are slidably mounted and guided in the bifurcated members 63 which are adjustably mounted on the shaft 63^a. This shaft is fixedly mounted on the extended arms 84^a of the frame member 84.

The right hand ends of the tubular rods are the supports for the lapping arms and are slidably mounted in the pivoted bearings 59 and 60. These bearings are of the hinge type and have a common support in the shaft 58 which is fixed in the frame 84.

The frame 84 is employed to retract and advance the lapping arms and another frame 68 is used to open the arms. The two frames

are mounted on a shaft 71 which serves as a pivot. For operating the frame 68 I provide a cylinder 64 in which is a piston 64^a having a piston rod 65. The rod 65 operates a toggle joint composed of the links 66 and 67 which are rotatably mounted in the frames 68 and 84 on the pin 69 and the pin 70. The straightening of the toggle joint causes the outer frame 68 to swing back on the shaft 71 which also serves as a pivotal mounting for the vertical cylinder 64. While the frame 68 is moving away from the machine it pulls on the chains or cables 72 through the links 73 which are fixedly mounted on the shaft 74 in the frame 68. Latches 76 are pivoted in the pivoted slide bearings 59 and 60, on pins 77 and held out of engagement with the tubular rods 61 by the springs 77^a. The chains pull on the levers 75 of the latches 76 rotating them to right and left respectively. The rotation of the latches about their pins causes the lower surfaces of the latches to clamp down on the tubular rods 61 preventing them from sliding and holding them in place while they are moved away from the work. These latches are operated and set by a very slight movement of the frame 68 and during the time the frame is moving the rest of the way the chains pulling on the levers 75 of the latches cause the lapping arms to separate by the rotation of their supporting bearings 59 and 60 about the shaft 58.

During the time that the latching and spreading of the arms is taking place, I bypass the air to a horizontal cylinder 81 by means of the cam 78 which is rigidly mounted on the frame member 68. Before the frame 68 has completed its outward movement the lower surface of cam 78 engages a whistle valve 80 located in the air line, so as to admit air through a pipe 80^a which is connected to the said horizontal cylinder 81. This cylinder is rigidly mounted on the under side of the main bed of the machine. The valve is so arranged that the by-passing of the air into the cylinder 81 does not exclude the air from the cylinder 64 because it is necessary to maintain pressure within the cylinder 64. Within the cylinder 81 is a piston 81^a whose piston rod 82 is connected to the frame 84 by means of a link 83 having pivot pins 85 and 86, one to the piston rod and one to the frame 84.

The frame 84 is normally held in locked position by means of the gravity actuated latch 87, which is mounted pivotally by means of a pin 88 to the frame 1, and has a notched end 89 which engages the lug plate 90 fast on the frame 84. As can be seen, I have slotted the hole 91 in the link 83 which receives the pin 86 on the frame. This slot is provided to allow for the movement required to release the latch 87. The link 83 has its inner end formed to engage the end 87^a of the latch and thus release it from position of latching

the frame. When the latch 87 has been released, the left end of the slot 91 will bear against and push on the pin 86 which results in moving the frame away from the machine carrying with it the lapping arms, their guides, and the lubricating hose. 70

In operating the machine I first index the crank shaft between centers, as has been described. With the manually operated three way control valve 81^a I admit air through the pipe 92^b into the right hand end of the horizontal cylinder 81 (Figures 4 and 5) whose piston pulls the frame 84 towards the machine until the latch 87 drops over the latch bar 90 and locks the frame 84 in place. This action also pulls the frame 68 inwardly because of the toggle. When the frames are in this position the upper whistle valve 92 will have been operated by the upper surface of the cam 78 and is so connected as to by-pass air through the pipe 92^b into the top of the vertical cylinder 64. This results in pulling down the rod 65 causing the toggle joint 67 to collapse and pull the frame 68 into place. While the frame 68 is moving into place the lapping arms are closed over the surface to be lapped by the springs 46, and as the frame 68 comes to rest it releases the pull on the chain which in turn releases the latch 76 and leaves the machine in condition to apply power and begin lapping. 95

Having thus described my invention, what I claim as new and desire to secure by Letters Patent, is:—

1. In a lapping machine, the combination of means for rotating a crank shaft, lapping members arranged in pairs to engage over and move with the surfaces of the crank shaft to be lapped, under power applied thereto by said shaft, and power operated means for applying and removing the lapping members from the said surfaces to be lapped after a predetermined number of rotations of the crank shaft. 100

2. In a lapping machine, the combination of means for rotating a crank shaft, lapping members arranged in pairs to engage over and move with the surfaces of the crank shaft to be lapped, under power applied thereto by said shaft, and power operated means for applying and removing the lapping members from the said surfaces to be lapped after a predetermined number of rotations of the crank shaft, said rotating means comprising members for giving a predetermined position 110 of the crank shaft with relation to said lapping members. 115

3. In a lapping machine, the combination of means for rotating a crank shaft, lapping members arranged in pairs to engage over and move with the surfaces of the crank shaft to be lapped, under power applied thereto by said shaft, and power operated means for applying and removing the lapping members from the said surfaces to be lapped after a 120 130

predetermined number of rotations of the crank shaft, said rotating means comprising members for giving a predetermined position of the crank shaft with relation to said lapping members, and means for inhibiting actuation of said rotating means until said predetermined position is attained.

4. In a lapping machine, the combination of means for rotating a crank shaft, lapping members arranged in pairs to engage over and move with the surfaces of the crank shaft to be lapped, under power applied thereto by said shaft, and power operated means for applying and removing the lapping members from the said surfaces to be lapped after a predetermined number of rotations of the crank shaft, said rotating means comprising members for giving a predetermined position of the crank shaft with relation to said lapping members, and means for preventing application of the lapping members until said predetermined position has been attained.

5. In a lapping machine, the combination of means for rotating a crank shaft, lapping members arranged in pairs to engage over and move with the surfaces of the crank shaft to be lapped, under power applied thereto by said shaft, and power operated means for applying and removing the lapping members from the said surfaces to be lapped after a predetermined number of rotations of the crank shaft, said rotating means comprising members for giving a predetermined position of the crank shaft with relation to said lapping members, and means for inhibiting actuation thereof until said predetermined position is applied, and means for preventing application of the lapping members until said predetermined position has been attained.

6. In a lapping machine, the combination of means for rotating a crank shaft, lapping members arranged in pairs to engage over and move with the surfaces of the crank shaft to be lapped, under power applied thereto by said shaft, and power operated means for applying and removing the lapping members from the said surfaces to be lapped after a predetermined number of rotations of the crank shaft, said rotating means comprising members for giving a predetermined position of the crank shaft with relation to the lapping members at the start and finish of every lapping operation.

7. In a lapping machine, the combination of means for rotating a crank shaft, lapping members arranged in pairs to engage over and move with the surfaces of the crank shaft to be lapped, under power applied thereto by said shaft, and power operated means for applying and removing the lapping members from the said surfaces to be lapped after a predetermined number of rotations of the crank shaft, said means comprising a movable frame on which said lapping members

are mounted, and a member movable with relation to said frame and connected to the lapping members so as to open the same thereby releasing them from the crank shaft surfaces.

8. In a lapping machine, the combination of means for rotating a crank shaft, lapping members arranged to engage over and move with the surfaces of the crank shaft to be lapped, and means for applying and removing the lapping members from the said surfaces to be lapped, said means comprising a movable frame on which said lapping members are mounted, and a member movable with relation to said frame and connected to the lapping members so as to open the same thereby releasing them from the crank shaft surfaces, said lapping members having means to lock them in their open position.

9. In a lapping machine, the combination of means for rotating a crank shaft, lapping members arranged to engage over and move with the surfaces of the crank shaft to be lapped, and means for applying and removing the lapping members from the said surfaces to be lapped, said means comprising a movable frame on which said lapping members are mounted, and a member movable with relation to said frame and connected to the lapping members so as to open the same thereby releasing them from the crank shaft surfaces, and power means for actuating said frame and said movable member in a predetermined sequence.

10. In a lapping machine, the combination of means for rotating a crank shaft, lapping members arranged to engage over and move with the surfaces of the crank shaft to be lapped, and means for applying and removing the lapping members from the said surfaces to be lapped, said means comprising a movable frame on which said lapping members are mounted, and a member movable with relation to said frame and connected to the lapping members so as to open the same thereby releasing them from the crank shaft surfaces, and power means for actuating said frame and said movable member in a predetermined sequence, said sequence being as follows:—a movement of the movable member to open and lock the lapping members, a movement of both the movable frame and movable member to withdraw the lapping members, a movement of both the frame and the movable member to advance the lapping members, and a movement of the movable members to unlock and permit the closure of the lapping members over the surfaces to be lapped.

11. In a lapping machine, the combination of means for rotating a crank shaft, lapping members arranged to engage over and move with the surfaces of the crank shaft to be lapped, and means for applying and removing the lapping members from said surfaces

- to be lapped, said means comprising a movable frame on which said lapping members are mounted, and a member movable with relation to said frame and connected to the lapping members so as to open the same thereby releasing them from the crank shaft, and means for inhibiting the movement of the movable frames during the lapping operation.
12. In a lapping machine, the combination of means for rotating a crank shaft, lapping members arranged to engage over and move with the surfaces of the crank shaft to be lapped, and means for applying and removing the lapping members from said surfaces to be lapped, said means comprising a movable frame on which said lapping members are mounted, and a member movable with relation to said frame and connected to the lapping members so as to open the same thereby releasing them from the crank shaft, and means for inhibiting the movement of the movable frames during the lapping operation, and a means provided on the power actuated means to release said inhibiting means after said movable frame for opening the lapping means has moved sufficiently to open and lock the lapping means in place.
13. In a lapping machine, a lapping member comprising upper and lower lapping arms slidably mounted in a means for pivotally supporting said lapping means, and means for locking said lapping arms in a predetermined position when out of lapping position.
14. In a lapping machine, a lapping member comprising upper and lower lapping arms slidably mounted in a means for pivotally supporting said lapping means, means for locking said lapping arms in a predetermined position when out of lapping position, and means for releasing the locking means when the arms are advanced to lapping position.
